HOROLOGICAL BALANCE WHEEL HOLDING
AND ROTATING DEVICE

Victor L. Emanuel, Colorado Springs, Colo.

Application June 14, 1948, Serial No. 32,783

1 Claim. (Cl. 51—236)

2

My invention relates to a device for properly holding and rotating a horological balance-wheel during its pivot-polishing operation and pertains more particularly to means whereby a true centering or aligning of the pivot holding elements may be more quickly and accurately obtained and such centering maintained during the mounting of the balance-wheel in place.

The improved device contemplates a hollow pulley carrying member on which the pulley is non-shiftably and rotatably mounted and said hollow member adapted to receive a longitudinally adjustable pivot receiving rod or member with which a pivot holding element or adjustable plate is aligned. The invention also contemplates a centering pin or rod longitudinally slidable through the hollow pulley carrying member and adapted to engage the pivot receiving hole in the adjustable pivot-plate during installation and adjustment of the removable pivot-plate.

My improved device is of such construction that it may be readily attached or mounted on a watchmaker's lathe and power for rotating the balance wheel rotating pulley is received from the lathe driving shaft or pulley.

The objects and advantages of my invention will be readily comprehended from the following detailed description of the accompanying drawing wherein:

Figure 1 is a perspective view of a portion of a watchmaker's lathe with my invention applied thereto.

Figure 2 is a side elevation of my improved device, on a larger scale, removed from the lathe.

Figure 3 is a longitudinal sectional view, with portions in elevation, of the device as shown in Figure 2, with the pivot holding rod replaced by a centering pin.

Figure 4 is an end elevation as viewed from the right in Figure 2.

Figure 5 is a detail view, on a somewhat larger scale, partly in section, of the pivot holding end of the pivot holding pintle or rod shown in Figure 2.

In the particular exemplification, the device involves a supporting upright post 10, preferably of square cross-section at its upper end and a cylindrical lower end (which may be integral with or have a force fit in the lower end of the square section) adapted to fit into the socketed base 11, of the T-rest attachment of a watchmaker's lathe, the post being firmly clamped in place against rotation as for example by the hand screw member 12.

The upper square portion of the post is cross-drilled to receive a tubular or elongated non-rotating hollow member 13 whose longitudinal axis is arranged at right angles to the vertical axis of the post 10 and preferably provided, at a suit-

able distance from its outer end, with a socket or opening to receive the end of the thumb-screw 14 arranged in the tapped opening in the upper end of the post 10, as shown in Figure 3, whereby the member 13 is securely held in place against longitudinal and rotative movement.

The member 13 at its inner end is preferably provided with a flange 15 and with a rotatable grooved pulley 16 which, at one side, is provided with an elongated spacing hub 16^a adapted to take against the adjacent side of the post to maintain the proper spaced relation of the pulley relative to the post 10.

The pulley 16 is cross-drilled to slidably receive the balance-wheel controlling pin 17, which latter is held in its adjusted positions by a suitable friction spring 18 arranged intermediate the flanged or shouldered inner end of the member 13 and the inner adjacent side of the pulley 16. The free end of the spring 18 is adapted to frictionally engage pin 17 to maintain the latter in its longitudinally adjusted position.

The end of the squared portion of post 10 is also cross-drilled to receive the reduced outer end of the pintle 19; the reduced end being snugly driven into post 10 so as to rigidly hold the pintle against movement. The inner end of the pintle 19 is shouldered and provided with a further reduced externally threaded end 19^a adapted to receive the internally threaded thimble or sleeve 20, whereby the balance-wheel pivot holding plate 21 is clamped against the shoulder formed at the reduced inner end of pintle 19. The lower end of pivot holding plate 21 is preferably vertically slotted to fit onto the reduced end of the pintle to permit vertical and lateral adjustment of plate 21; and the upper end of the plate is preferably provided with a pivot receiving small hole as at 21^a.

40 The member 13 is adapted to receive and support a longitudinally adjustable balance-wheel pivot holding rod or member 22 which is closely or more or less frictionally fitted in the member 13 and held in its adjusted position by the thumb-screw 14 which extends through the hole in the member 13 as shown in Figure 3. The member 22 at its outer end is shown provided with a finger grasping portion or knob 22^a; while the end face of the member at its longitudinal axis is longitudinally drilled as at 23 (see Figure 5) to receive a pivot of a balance-wheel. The member 22, at the inner end and at the pivot receiving hole 23, preferably is cross-drilled as at 23^a communicating with the base of hole 23 (thus obviating the necessity of greater longitudinal drilling of hole 23), thereby accommodating a balance-wheel pivot of greater length or size.

45 In order to enable a quick and accurate centering or aligning of the pivot receiving hole 21^a in 50 pivot plate 21 with the pivot receiving hole 23 of

55 60

member 22, when the latter is inserted in member 13, I provide a centering pin 24, see Figure 3, of length sufficient to extend through the member 13 and the pointed end 24a adapted to enter the pivot receiving hole 21a in the upper end of the pivot plate 21. The outer end of the pin 24 preferably is provided with a finger grasping enlargement; and the pin preferably is closely fitted in the sleeve and after its pointed end 24a has entered the hole in the pivot plate 21, the pin may be held against movement by the thumb-screw 14, with the result that the pivot plate 21 will be held in correct position and be so maintained against rotative movement during the screwing-up of thimble or sleeve 20.

After the pivot plate has been centered and firmly clamped in place by sleeve 20, thumb-screw 14 is released, centering pin 24 withdrawn from the elongated member 13 and the pivot holding member 22 is slid into the holding member to an extent commensurate with the size of balance-wheel to be operated on; the member then being secured against movement by the thumb-screw 14. As is apparent, the pivot receiving holes in the end of member 22 and in the pivot plate 21 will be in true alignment.

The pulley 16, loosely mounted on the elongated member 13, is intended to be driven by the belt 25 which extends about pulley member 26 provided with two grooves of different circumferences whereby the pulley 16 may be driven at different speeds; with belt 25 arranged in small groove 26a, pulley 16 will be driven at a low speed which is especially desirable in balance-wheel pivot straightening operations.

The pulley member 26 at one side has a trunnion 26b adapted to fit into a chuck secured to the end of the usual driving shaft of the lathe.

After the balance-wheel has been properly positioned between the end of member 22 and pivot holding plate 21, the fork or controlling pin 17 is longitudinally adjusted in pulley 16 so that the end of the pin 17 will engage the balance-wheel and cause the latter to rotate during rotation of pulley 16; pin 17 being longitudinally adjustable adapts it to different sizes of balance-wheels. As the pulley 16 is held against movement longitudinally of the member 13 by the flange 15 and the hub portion 16a the pulley 16 is maintained in transverse alignment with the chucked pulley 26 secured to the drive shaft of the lathe; adjustments for different sized balance-wheels being made by sliding or slightly turning the frictionally held fork or pin 17.

In balance wheel holders as heretofore made, the watchmaker makes adjustment of the pivot plate by sighting the position of the plate relative to the end of the pivot receiving member, shifting the vertical position of the pivot plate until the balance-wheel appears to be in vertical position and then tightens the plate clamping set-screw, whose turning movement frequently causes the pivot plate to slightly shift laterally. With my improved device provided with the rigidly held member, the centering pin 24 is initially inserted through the member and the pivot plate is shifted to position where the top or point of the centering pin engages the hole in the pivot plate. The centering pin is kept in this position during screwing-up of the pivot plate clamping thumb-screw thereby holding the pivot plate against movement and ensuring true alignment between the pivot plate hole and the hole 23 in

the end of the rod 22—an operation which can be more quickly and accurately performed. After the pivot plate hole 21a has thus been centered with the pivot receiving hole 23 in rod 22 and plate 21 securely fastened in position, centering pin 24 is withdrawn and pivot holding pin 22 substituted and the balance wheel to be operated on is then put in place with one pivot inserted in hole 21a and the other pivot inserted in hole 23 of rod 22, which latter is then held against accidental outward movement by screwing down thumb-screw 14. Fork or pin 17 is then moved outwardly until it engages the spokes of the balance wheel, causing the latter to rotate with pulley 16. The balance wheel then is in position for the watchmaker to manually perform the usual pivot straightening and/or polishing operations which generally are performed by means of suitable pivot straightening tweezers while the 20 polishing is accomplished by the use of small "jasper-slips" or sapphire slips held against the lower surface of the pivots during balance wheel rotation. After the operation on the pivot held by pivot-plate 21 has been completed, the balance-wheel is reversed because the pivot seated in the aperture of pin 22 is not accessible for these operations.

My improved device has been described in terms of description and not as terms of limitation; certain details of modification may be possible without, however, departing from the spirit of my invention as defined in the appended claim.

What I claim is:

In a horological balance wheel holding and rotating device, the combination of a vertically disposed supporting post with a horizontally extending pintle rigidly mounted on the lower part of the post; an upstanding balance wheel pivot receiving apertured plate adjustably mounted at its lower end on said pintle and arranged transversely thereof; a horizontally disposed hollow member in the upper end of said post, arranged parallel with said pintle and having an annular flange at its inner end; a pulley, with an elongated hub, for maintaining the pulley against said annular flange, rotatably mounted on said member and provided with a longitudinally adjustable balance wheel controlling pin; a pivot holding rod slidably and removably mounted in said hollow member and provided at its inner end and at its longitudinal axis with a balance-wheel pivot-receiving aperture; and means for holding said rod in its adjusted position.

VICTOR L. EMANUEL.
